UNITED STATES PATENT OFFICE.

HOWELL CHENEY, OF SOUTH MANCHESTER, CONNECTICUT, ASSIGNOR TO CHENEY BROTHERS, OF SOUTH MANCHESTER, CONNECTICUT, A CORPORATION OF CONNECTICUT.

SCARF.

1,174,927.

Specification of Letters Patent.

Patented Mar. 7, 1916.

Application filed October 16, 1915. Serial No. 56,176.

To all whom it may concern:

Be it known that I, HOWELL CHENEY, a citizen of the United States of America, residing at South Manchester, Connecticut, 5 have invented a new and useful Scarf, of which the following is a specification.

My invention relates to scarfs for neck-wear, the object broadly stated, being to provide an improved construction which 10 will enable the owner to easily clean, renovate or press the same.

In the accompanying drawings: Figure 1 is a view of the scarf as it would appear ready for use, certain parts being broken 15 away. Fig. 2 is a view of the scarf opened up and showing the lining.

The scarf comprises an inner lining member and an external removable cover member. The lining member is indicated at 1, 20 the cover member at 2. The lining member is provided with two fan-tail ends 3—4 while the cover member is also provided with two fan-tail ends 5 and 6, forming tapering pockets when folded. The cover 25 member is of sufficient size to inclose and hide the lining when folded as shown in Fig. 1. Suitable fastening devices are provided along or adjacent to the edges of the cover member to enable the cover member to 30 be retained in its folded form. Preferably, these fastening means comprise a ball and socket indicated respectively at 7, 8. The narrower part of the lining member and the cover member constitute the neckband portion of the scarf, while the wider ends con-

stitute that part which is tied and exposed. The narrower part of the lining member when folded so embraces the narrower part of the lining member as to hold it against endwise displacement in and relatively to 40 the cover member.

When the scarf has become wrinkled or soiled, it is possible to easily clean, renovate or press the same by simply disengaging the fastening members, opening up the cover 45 member and removing the lining member whereby these two members may be separately washed or otherwise cleaned and pressed and then reassembled, as shown in Fig. 1. 50

The cover member may be a fabric of any appropriate color or design, while the internal lining member is a fabric preferably having a relatively rough surface and also preferably of coarser and heavier material 55 than the cover portion so as to afford the proper foundation or support for the cover.

What I claim is:

In a scarf, a fabric cover portion having fan-tail ends, an internal removable lining 60 portion also having fan-tail ends, detachable fastening devices adjacent to the edges of the cover portion and independent of said lining for securing said edges together longitudinally, forming tapered end pockets 65 connected by an intermediate relatively narrow neck band, said neck band having a contracted passage of less width than the width of the fan-tail ends of said lining. 70

HOWELL CHENEY.
